UNITED STATES PATENT OFFICE.

HENRY MASON YOUNG, OF MINNEAPOLIS, MINNESOTA, ASSIGNOR TO
WILBUR F. STEELE, OF STEELE, DAKOTA TERRITORY.

STEAM GENERATING AND HEATING APPARATUS.

SPECIFICATION forming part of Letters Patent No. 358,824, dated March 1, 1887.

Application filed January 25, 1887. Serial No. 225,468. (No model.)

To all whom it may concern:

Be it known that I, HENRY MASON YOUNG, a citizen of the United States, residing at Minneapolis, in the county of Hennepin and State 5 of Minnesota, have invented certain new and useful Improvements in Apparatus for Heating and Lighting Cars and other Structures, and for Cutting off the Heat and Extinguishing the Lights, of which the following is a 10 specification.

My invention relates to an apparatus for generating heat in cars and other structures by hydrocarbons, gas, vapor-fuel, and steam or water; and it consists in the construction, 15 arrangement, and adaptation of the apparatus and its several parts, which will be more fully described, and pointed out in the claims.

One object of my invention is to provide simple and effective means for supplying fuel to 20 cars and other structures in a compact form, so that it can be readily and easily handled and safely and securely stored and employed.

A further object of my invention is to provide a cheap and effective apparatus for utilizing such fuel in generating heat, and for distributing and employing the same where desired.

A further object of my invention is to provide means for controlling and regulating the 30 heat thus generated, and, when necessary, stop its production instantly by positive means, or by means set in operation by a collision, or any extraordinary concussion of the cars with other cars or objects.

35 A further object of my invention is to provide means for extinguishing the lamps or other lights used in cars and other structures instantly by positive means, when desired or by means set in operation by a collision or any 40 accident to the cars.

A further object of my invention is to provide for the location of or removal to a safe distance of the fuel supply in case of an accident or any extraordinary concussion of the 45 cars.

The principal object of my invention is to provide an apparatus by which cars and other structures where it is used may be kept at any required degree of heat in any climate, and 50 thereby rendered comfortable and enjoyable,

and in case of accident or collision, when human life is endangered or the destruction of property made probable, the production of such heat will be instantly cut off, the supply of fuel removed, the lights, if any, extinguished, and all 55 danger by burning and consequent loss of life and property prevented and obviated.

I am aware that cars and other structures have been heated by steam and by water by passing the same through coils of pipes within 60 and around the interior of the same, but, so far as I know, with only partial success and at great cost and expense and without providing for the safety and security of the lives of the passengers and occupants or the protection of 65 property.

The object and purposes above set forth, as well as the difficulties, insufficiencies, and defects in the apparatus heretofore used, I have accomplished and overcome by the apparatus 70 hereinafter described, and illustrated in the drawings forming a part of my specification, in which like letters of reference refer to similar parts, and in which—

Figure 1 is an elevation of a portion of a 75 passenger-coach with my improved apparatus arranged therein. Fig. 2 is an enlarged detail view of my heat-generating apparatus. Fig. 3 is a plan view of Fig. 2. Fig. 4 is an enlarged sectional detail view of the device 80 for charging the liquid fuel-holding reservoir. Fig. 5 is an enlarged view of the automatic detachable self-closing valves of the liquid-fuel-holding reservoir. Fig. 6 is a perspective view of the coupling-head of the fuel-supply 85 pipe detached.

I shall first describe my apparatus and its operation when water is used as the heat-conducting medium.

A' represents the floor, A² the body, and A³ 90 the roof, of the car, of the ordinary construction.

In one corner of the car, or at any other convenient point near the floor, is set a hollow steam and water tight vessel, B', from which the 95 main circulating-pipe B² leads upward to a point near the roof A³, and from thence by a branch, B³, in a substantially horizontal line to another upright section, B⁴, and from thence downward to the main radiator coil or other 100

means for imparting the heat to the atmosphere in the coach. Any form of radiator-coil or other means may be employed to impart the heat to the surrounding atmosphere, 5 being modified according to the location and uses of the apparatus; but generally a simple system of sinuous coils beneath the seats will be used when the apparatus is used in passenger-coaches, these coils being indicated in 10 Fig. 1 by pipes B³.

At the extremity of the system of piping, or at the farthest point from the generating apparatus, the piping is led into a return-pipe, B⁶, which is led back to and connected into 15 the bottom of the generating-vessel B', as shown, thus completing the circuit of the piping. The two sections B² B³ are connected at one or more points between the generating-vessel B' and the branch B³ by one or more 20 cross-branches, B⁷, and a feed-pipe, B⁸, will be connected into the system at any suitable point to enable the necessary water to be supplied thereto.

The portion of the apparatus comprised in 25 the sections of the piping B² B³ B⁴ B⁵ is a very important feature of the apparatus, as an air-cushion is formed in the pipes B² B³ B⁴ above the water-line, (indicated by the dotted line *a* in Fig. 1,) which is brought in through pipe B⁸, 30 and by means of such air-cushion the necessary circulation of the water is secured in the pipes and coils. When the water becomes heated in the generating-vessel B', it rises in the pipe B², compresses the air in the sections B² B³ B⁴ above the water-line, and assists the 35 water to be forced over through the branches B⁷ into the sections B⁴ B⁵, and thence return through the pipe B⁶ to the generator B'. By this simple arrangement it is possible to construct 40 an apparatus with the radiators or coils at or near the level of the generator or source of water-supply, which is a very great advantage under any circumstances, especially in passenger-coaches, where it is not convenient 45 to place the generator below the flooring. The location of the generator is thus made independent of the position of the radiators, which may be placed above or below the generator, the air-cushion in the piping B² B³ B⁴ being 50 sufficiently compressed to assist the water to be forced through the piping and circulate through them. The circulation is thus due to the opposing action of the expanded or heated water and the compressed air, which makes 55 the apparatus more certain in its operation, and is not liable to become disarranged.

Another very important advantage is that the circulation is secured by the closed system of piping, thereby avoiding the necessity 60 of exposing the hot water in open tanks or passing it through traps or other apparatus, where a large amount of the heat is lost by radiation.

Generally only one of the branches B⁷ will 65 be in operation and required; but two or more will be placed in the system as a precaution

and to insure the apparatus against accidental obstruction.

The generator consists of a flat oval-shaped cast-metal chamber, into the top of which the pipe B³ is fitted, and into the bottom of which the return-main B⁶ is led.

In Fig. 2 the generator is shown with a series of pins inserted or cast into it and projecting upward into its interior and downward outside of the same, the function of these pins being to conduct the heat through the wall of the generator and impart it more freely to the water therein than the same degree of heat would be imparted thereto by the main 75 walls of the generator.

When applied to a railway passenger-coach, the fuel used to generate the heat in the system will usually be some form of the hydrocarbons, and an approved form of apparatus 80 for utilizing such fuel is shown in the drawings.

D' represents a large hydrocarbon-burner having an inclosed chamber, e', surrounding the central tube, e², beneath which small burner 90 D² is placed. The hydrocarbon is supplied by a feed-pipe, d', to the inclosed chamber e', in which it is vaporized by the heat from the burners D' D², and from thence passes by a pipe, d², in the form of inflammable gas or vapor. The small burner D² is connected to the pipe d² by a short branch, d³, in which a valve, d⁴, is placed to shut off the supply of the gas. The branch pipe d³ is smaller than pipe d², as only a small amount of gas is required to pass 100 to the burners D' D², or just sufficient to supply them, the greater bulk of the gas passing to the large burner D³ beneath the generator B'. The functions of the burners D' D² are merely to vaporize the hydrocarbon to supply 105 the large operative burner D³, so that the liquid hydrocarbon is not exposed to the flame at any time, but is vaporized at a point entirely distinct from the main burner D³ and at a safe distance from its flame.

The pipe d² is not connected directly to the burner D³, but ends at d⁵ in a short contracted nozzle opposite the flaring end d⁶ of the entrance to the burner D³, so that the vapor is compressed by the nozzle and passes to the burner 115 D³ with considerable force, carrying a large amount of air with it, which enters at the gap between the nozzle d⁵ and the flaring end d⁶, thereby adding to the inflammability and heat-producing power of the gas.

The generator B', burners D' D² D³, and the pipes d' d² d³ will be supported by any suitable frame-work or stand, and may be surrounded by a casing of any suitable material, these parts not being shown in the drawings, 125 as they form no part of the invention, and are not necessary to its operation.

The tank E, for holding the supply of hydrocarbon, will be connected to the end of the pipe d', at a point sufficiently above the burner D' to insure the necessary "head" to supply 130 the liquid, and when the apparatus is used

on passenger coaches the tank will be made spherical in form and set upon the roof A³ and connected to the pipe d' by a detachable joint, so that in event of an accident the tank will 5 become detached from the coach and roll off, as hereinafter described.

In Figs. 5 and 6 the manner of forming the detachable connection between the tank E and the pipe d' is shown. The tank E is supplied 10 with a valve, g', adapted to be seated on a seat, F', by a spring, g'', from the inside, so that when closed the contents of the tank will not flow out. The end of the pipe d' next to the tank E is provided with an enlarged head, F'', 15 containing a valve, g³, adapted to be closed from the inside by a spring, g⁴, so that when closed the contents of the pipe cannot flow out. The contiguous surfaces of the parts F' F'' are fitted closely, so that when placed together the 20 joint between them will fit tight, and a rubber gasket or other suitable packing will be placed between them to render the joint liquid-tight.

Upon one side of the edge of the head F² 25 two small lugs, h' h², (see Fig. 6,) are formed, and on the other side of the head a lever, h³, is pivoted, having its upper end, h⁴, formed to correspond to the lugs h' h², the end of the lever h⁴ projecting over the edge of the part F', 30 which is made slightly angular, and thus holding the two parts F' F'' locked together so long as the lower end of the lever h³ is pressed outward, but may be detached by pulling the lever inward and downward by the cord i'. It 35 will thus be readily seen that if the lever h³ be pulled downward the tank E will be left resting only upon the small joint F' F'', and will roll off from the car by a sufficient jar.

Attached to the body of the car at any convenient point is a small bracket, H', having a 40 small hollow socket, H², upon which a heavy metal ball, K, rests loosely, and is connected by a cord or chain, i, to the end of the lever h³, the ball K being so poised upon the bracket H' that any sufficient jar will displace the ball and cause it to fall and pull the lever h³, release the tank and leave it free to roll off and away from the car, and avoid the danger of 45 the leakage of the hydrocarbon in event of accidents. The two valves d⁴ d' are also connected by a cord or chain, i', to the ball K, so that the falling of the ball will shut off the supply of the gas to the burners, and thus avoid danger of fire from that source. By 50 these simple arrangements, in event of an accident, the concussion will throw the ball K from the bracket and disconnect the joint F' F'', and leave the tank E free to roll off from the car and away from danger of the contents 55 of the tank being ignited and endangering the lives of the passengers.

The tank E, being spherical, will readily roll out of the way when detached, and the spherical form of the tank is an important advantage.

The valves g' g³ are provided with stems g⁵ g⁶, projecting toward each other, and of a proper

length to come in contact and force both valves open, as in Fig. 5, when the joints F' F'' are in contact, so that the flow of the liquid is unobstructed when the joint is intact, but release the valves and allow the springs to seat the same immediately upon the disengagement of the parts, and thus prevent the escape of the liquid when the tank is released by the dropping 75 of the ball K, as before described.

The stem g⁷ of the valve g³ is continued downward into the pipe d', and is provided with a plunger, g⁸, partially filling the pipe d', the function of this plunger being to form a 80 sudden suction upward in the pipe d' when the tank E is disconnected, to cause a sudden backward draft upon the liquid and gas in the burners, and thus suddenly extinguishing the burners.

Any sudden back-suction upon the liquid or gas will produce a slight vacuum in the burners, and will instantly extinguish them.

The tank E is provided on the side opposite to the valve g' with another valve, n', seated 90 from the interior of the tank, to prevent the escape of the liquid, and provided with a stem, n'', adapted to project upward into a screw-socket, n³, as shown in Fig. 5.

Fig. 4 represents the discharge end of a supply can or tank, M, from which the tank E is to be supplied, and is provided with a screw-plug, t', adapted to be screwed into the socket n³.

t' is a valve in the filling-can M, seated from 95 the interior, and provided with a stem, t³, the two stems n³ t³ being adapted to come in contact and press the two valves n' and t² open when the plug t' is screwed into the socket n³, and thus allow the contents of the can M to flow 105 into the tank E. By this simple arrangement, when the tank E is to be charged with the hydrocarbon, it is only necessary to invert one of the cans M filled with the liquid and screw its plug t' into the socket n³, which will open the 110 valves n' t² and allow the liquid to flow from the cans M into the tank. These cans M, charged with the hydrocarbons, will be placed at suitable intervals along the line of the railroads, so that the tanks E can be replenished 115 when required.

The burner D³ may be connected directly to the pipe d', instead of being arranged with the gap between the nozzle d³ and the burner D³, or any well-known form of burner may be employed instead of said burner.

Two of the levers h³ may be used, one on each side of the joint F' F'', instead of the lugs h' h², or any other suitable form of easily-detachable lock-nut mechanism may be employed.

N' is a small cylinder supported in any suitable manner from the body of the car and provided with a plunger, N², connected by a cord or chain, i³, running over pulleys N³ to the ball K, so that the falling of the ball will draw the plunger upward and compress the air therein, and force a sudden current through a pipe, N⁴, leading to a point adjacent to each

of the lamps P in the car and extinguish them.

I have only shown one of the lamps P; but it will be readily understood that the pipe can be conducted to all the lamps in the car and extinguish them all at once. The cylinder N' may be arranged so that the plunger is forced downward or in any other direction, the results being the same.

10 Above the ball K is a ring, K², through which all the cords leading therefrom pass, so that no matter in what direction the ball falls it will pull the cords and extinguish all the fires and lights in the car instantaneously.

15 Having described the construction and arrangement of my apparatus, I shall now describe its operation.

Water is brought in through the pipe B⁸ from any source of supply, but preferably

20 water impregnated with salt or other like material or with liquids, until the pipes B⁵, B⁶, B², and B⁴ are filled, the latter named up to the dotted line a, Fig. 1. Hydrocarbon is then permitted to flow through the pipe d' from 25 the tank E to the chamber e', within and above the burners D' D², where it is ignited and vaporized, the vapor or gas thus produced passing from thence through the pipe d' to the burner D³, where it is ignited, heating the

30 water in the generator B' and causing it to expand and flow up through the pipe B² and, by reason of the air-cushion formed in the pipes B², B³, and B⁴, above the upper cross pipe or branch B⁷, the flow through the lower

35 pipes B⁷ being cut off by the cock therein, to pass through the upper cross pipe or branch, B⁷, down pipe B⁴, and around the coil B⁵, returning to the generator through pipe B⁶, where it is reheated and by the same means

40 caused to pass continuously and rapidly through the circuit of piping, as described, thereby heating the interior of the car or other structure, as required, the degree of heat being regulated by the hydrocarbon supply and

45 any suitable form of generator and any convenient form of hydrocarbon vaporizer or conductor may be used instead of those illustrated.

I have illustrated means and mechanism for 105 arresting the flow of hydrocarbon, its vaporization and burning, and the extinguishment of the lights, if any; but it will be understood that other means and ways may be devised for accomplishing the same results.

I desire to have it understood that I do not limit myself to the specific means described and illustrated for accomplishing the results herein named for producing heat and arresting its production, or for extinguishing lights when 115 an accident or severe concussion occurs in cars or other movable structures, as I claim that my invention covers any such means and appliances.

It is obvious that many changes may be 120 made in the construction and operation of the apparatus described and illustrated without departing from the nature or principle of my invention.

Having thus described my invention and its 125 operation, what I claim, and desire to secure by Letters Patent, is—

When steam is used as a medium for conducting heat, the generator B' only is filled with water and heated, as above described. 70 As steam is generated it passes up into pipe B² and may be conducted directly into the coils B⁵ by closing said pipe B² by any suitable means above the lower branch B⁷; or it may pass through the pipes B², B³, and B⁴ into 75 said coils B⁵, returning to the generator B' through the pipe B⁶ either as steam or water, when it will be reheated or vaporized and caused to flow through the same system of pipes.

It will be understood that the production of steam, as well as the production of heat for its generation, will and may be arrested in the same manner and by the same means employed as when water is used as the conduct- 85 ing medium.

I have illustrated my apparatus as employed in a car; but it will be understood that it may be used, and I contemplate using it, in houses, stores, and other buildings, as well as in ships 90 and vessels, or wherever heating is required.

I have provided in my apparatus for the carrying of a fuel-supply and the production of fuel; but it will be understood that other fuel may be used instead of and in the place 95 of the fuel which I provide.

As illustrated, the radiators consist of pipes; but it will be understood that other forms of radiators may be used, and especially when steam is employed as the heat-conducting me- 100 dium.

Any suitable form of generator and any convenient form of hydrocarbon vaporizer or conductor may be used instead of those illustrated.

I have illustrated means and mechanism for 105 arresting the flow of hydrocarbon, its vaporization and burning, and the extinguishment of the lights, if any; but it will be understood that other means and ways may be devised for accomplishing the same results.

I desire to have it understood that I do not limit myself to the specific means described and illustrated for accomplishing the results herein named for producing heat and arresting its production, or for extinguishing lights when 115 an accident or severe concussion occurs in cars or other movable structures, as I claim that my invention covers any such means and appliances.

It is obvious that many changes may be 120 made in the construction and operation of the apparatus described and illustrated without departing from the nature or principle of my invention.

Having thus described my invention and its 125 operation, what I claim, and desire to secure by Letters Patent, is—

1. In an apparatus for heating cars and other structures by water, the combination of a water-heater, heat-radiators, and intermediate pipes containing an air compression and expansion chamber near their tops and provided with a cross pipe or branch below said chamber, whereby by the action of the air in 130

- said chamber the circulation of the water through the radiators and back to the heater is assisted and facilitated, substantially as described.
5. 2. In an apparatus for heating cars and other structures by water, the combination of a water-heater, heat-radiators, and intermediate pipes containing an air compression and expansion chamber and having a branch or cross pipe beneath said chamber, the latter being water-sealed at the point farthest from the entry therein and expulsion of the water therefrom, wherein by the opposing action of the expanded or heated water and the compressed air caused by the expansion of the water the circulation of the heated water through the radiators and back to the heater is facilitated, substantially as described.
15. 3. In an apparatus for heating cars and other structures, the combination, with a water-heater and heat-radiators, of intermediate pipes constructed and arranged to form an air-chamber between said water-heater and heat-radiators, whereby the circulation of the heated water through the radiators and back to the heater is assisted and facilitated, substantially as described.
25. 4. The combination, with a burner and a pipe leading thereto, of a detachable reservoir and devices for uniting said pipe and reservoir, and means for instantly disengaging said devices, substantially as described.
35. 5. In a heating apparatus for cars and other structures, a self-heating hydrocarbon-vaporizer and its cut-off valve, in combination with a stationary bracket, a weight, and means for instantly closing said valve, substantially as described.
40. 6. The combination of the hydrocarbon-receptacle, a burner, a heat-generator, lamps or light-burners, a pipe connecting said lamps or light-burners, and means for extinguishing the flame in the burner and in the lamps or light-burners, substantially as described.
45. 7. The combination of a detachable hydrocarbon holder, a feed-pipe, a vaporizer, a vapor-burner having a valve, and means for automatically operating said valve and for detaching said holder, substantially as described.
50. 8. The combination of the hydrocarbon-holder E, the feed-pipe d', the burners D', D², and D³, the generator B', and the valves d⁴ d⁷, with means for automatically operating said valves for cutting off the supply of hydrocarbon and gas, substantially as described.
55. 9. The combination of the removable hydrocarbon tank or holder E, the feed-pipe d' leading therefrom, the self-acting valves g' g³, and means for disconnecting said holder and feed-pipe, whereby, when the two latter are disengaged, the said valves automatically close them, substantially as described.
60. 10. The combination of the hydrocarbon-holder E, having the seat F', the feed-pipe d', having the head F², the self-acting valves, and

means for disconnecting said joints, whereby, when the latter are disengaged, said valves will automatically close, for the purpose set forth, substantially as described.

70. 11. The combination of the hydrocarbon receptacle E, having the seat F', the feed-pipe d', having the head F², provided with lugs h' h², for holding said joints together, the pivoted lever h³, having a lug h⁴, at its upper end, the valves g' g³, and means for operating said lever, substantially as described.

75. 12. The combination of the burners, the hydrocarbon-holder E, and the feed-pipe d', provided with self-closing valves, the plunger g⁸, partially filling said feed-pipe, and means for disconnecting said holder and feed-pipe, whereby, when the two latter are disengaged, said plunger will produce an upward suction through the feed-pipe and cause a sudden upward draft upon the liquid and gas and suddenly extinguish the lights of the burners, substantially as described.

80. 13. The combination, with a railway-car and a detachably-secured hydrocarbon holder or receptacle located outside of said car, of mechanism for automatically and instantly detaching or removing said receptacle, substantially as described.

85. 14. The combination of the supply or filling can M, provided with a screw-plug, t', and the hydrocarbon-holder E, having a screw-socket, n³, with the self-acting valves t⁴ and n⁴, provided with the stems t⁵ and n⁵, and arranged within said filling-can and holder for the purpose stated, substantially as described.

90. 15. In a heating apparatus for cars and other structures employing hydrocarbon-vapor fuel, the combination of heat-radiators, a generator, a vapor-burner, a hydrocarbon-vaporizer, an automatically detachable and removable hydrocarbon-holder, connecting-pipes, and means for instantly cutting off the hydrocarbon-supply and extinguishing the flame from the burner and the lights in the car or structure, substantially as described.

95. 16. In an apparatus for heating cars and other structures by water and hydrocarbon vapor, the combination of heat-radiators, a water-heater, a vapor-burner, pipes connecting the heater and the radiators, one or more cross-pipes, and an air-chamber between the heater and the radiators wherein by the compression and expansion of the air the passage of the water is assisted or facilitated through the radiators and back to the heater, substantially as described.

100. 17. In an apparatus for heating cars and other structures, the combination of a water-supply conduit, a water-heater or steam generator, a vapor-burner, a hydrocarbon-vaporizer, a spherical detachable and removable hydrocarbon-holder having inlet and outlet openings and provided with internal yielding and retaining valves mounted on rigid stems for admitting, retaining, and discharging the hydrocarbon therefrom, pipes connecting said holder, vaporizer, and burner, heat-radiators, and pipes

connecting the water-heater or steam-generator with said radiators, substantially as described.

18. In a portable apparatus for heating cars and other movable structures by water or steam and hydrocarbon-vapor fuel or gas, the combination of a water-supply conduit, a water-heater or steam-generator, a vapor or gas burner, heat-radiators, pipes connecting the water-heater or steam generator and the heat-radiators, an air-chamber in the pipes between the water-heater and the heat-radiators operating to assist the passage of the water through the radiators and back to the heater, a hydrocarbon-holder, a hydrocarbon-vaporizer, and means for instantly detaching and removing the hydrocarbon holder and arresting the production of the vapor fuel or gas and for extinguishing the flame and lights in such structures, substantially as described.

19. In an apparatus for heating cars and other structures by water or steam and vapor

fuel or gas, the combination, with the hydrocarbon-holders, the vapor-burner, and the light-extinguishing air-compressor and conduit, of a ball mounted on a sustaining-support, chains or cords connected with said ball passing through or over suitable guides between it and said holder, burner, and air compressor and conduit and connected thereto by mechanical means, whereby when said ball is dislodged from its support and falls said hydrocarbon-holder is detached from its connections and rendered easily movable, the flow of hydrocarbon therefrom is cut off, and the flame in the vapor-burner and the lights are instantly extinguished.

In testimony whereof I have hereunto set my hand in the presence of two subscribing witnesses.

HENRY MASON YOUNG.
